UNITED STATES PATENT OFFICE.

GEORGE A. THOMPSON, OF BROOKLYN, NEW YORK.

WINDOW-SCREEN.

SPECIFICATION forming part of Letters Patent No. 291,549, dated January 8, 1884.

Application filed June 23, 1883. (No model.)

To all whom it may concern:

Be it known that I, GEORGE A. THOMPSON, of the city of Brooklyn, in the county of Kings and State of New York, have invented a new and Improved Window-Screen, of which the following specification is a full, clear, and exact description.

This invention relates to that class of window-screens which are automatically raised and lowered with the lower sash; and the invention consists, principally, in the combination of a window-frame with a box, screen, and rod having knobs, and with split guide-tubes which receive said knobs, all as hereinafter more fully described; also, in the details of improvement hereinafter more fully pointed out.

In the accompanying sheets of drawings, Figure 1, Sheet 1, is a perspective view of lower part of a window provided with my improvement. Fig. 2, Sheet 2, is a vertical transverse section of the same. Fig. 3, Sheet 2, is a detail view of the screen and its attachments; and Fig. 4, Sheet 2, a detail view of one of the guide-tubes.

Similar letters of reference indicate corresponding parts in all the figures.

The letter *A* represents a window-frame, *a* being the upper and *b* the lower sash. Upon 30 the window-ledge and below the upper sash, *a*, is placed a box, *c*, which contains a spring-roller, *d*. Around this spring-roller is wound the screen or netting *e*. This netting is attached at one end to said spring-roller, while 35 its other end passes out of a slot in the box *c*,

as seen in Fig. 2. The upper end of netting *e* is fastened to a rod, *f*, said rod having knobs *g* at its ends, which enter and slide in vertical split tubes *h*, attached to the parting-strips between the window-sashes. The rod *f* is also provided with eyes *i*, which are adapted to be slipped over buttons *j*, (dotted in Fig. 1,) affixed to the lower sash, *b*. A handle may likewise be attached to rod *f*, as shown in Fig. 1.

The operation is as follows: The upper edge of the screen is attached to sash *b* by means of eyes *i* and buttons *j*, and on raising the sash the screen will be raised with it. On lowering the sash the spring-roller *d* will draw the slack of the screen into the box *c*, thus keeping the screen taut at any position of the sash. If it is desired to clear the window of the screen, the latter is unhooked from sash *b*, and will be drawn entirely into the box *c*.

I claim as my invention—

1. The combination of window-frame *A* with box *c*, spring-roller *d*, screen *e*, and rod *f*, having knobs *g*, and with the split guide-tubes *h*, which receive said knobs, substantially as 60 herein shown and described.

2. The combination of window-frame *A* with box *c*, spring-roller *d*, screen *e*, rod *f*, having knobs *g* and eyes *i*, and with the guide-tubes *h*, and buttons *j* on the lower sash, substantially 65 as specified.

GEORGE A. THOMPSON.
